(57) **CLAIM**

The ornamental design for a replacement end device for a caulking cartridge, as shown and described.

DESCRIPTION

FIG. 1 is a front view of the replacement end device for a caulking cartridge, where the front view, back view, right side view, and left side view are identical;

FIG. 2 is a top view thereof;

FIG. 3 is a bottom view thereof;

FIG. 4 is a perspective view thereof; and,

FIG. 5 is a cross-sectional view thereof.
